UNITED STATES PATENT OFFICE.

JOHN H. YOUNG, OF CONCORD, NEW HAMPSHIRE.

SKATE.

SPECIFICATION forming part of Letters Patent No. 406,609, dated July 9, 1889.

Application filed November 16, 1888. Serial No. 291,021. (No model.)

To all whom it may concern:

Be it known that I, JOHN H. YOUNG, a citizen of Great Britain, residing at Concord, in the county of Merrimac and State of New Hampshire, have invented certain new and useful Improvements in Skates, of which the following is a specification.

This invention relates to the actuating mechanism by which the sole and heel clamps of a skate are readily adjusted to fit various sizes of boots, and will be clearly understood by reference to the accompanying drawings, forming an inseparable part of the following specification, of which—

15 Figure 1 is a side view of a skate fitted with my improvements. Fig. 2 is a detached perspective view of the adjustable heel-clamp. Fig. 3 is a plan view of a skate, showing my improved adjusting and clamping mechanism as when opened ready for application to a boot. Fig. 4 is a broken elevation showing a modification of my improvements. Fig. 5 is a detached perspective view of one of my improved parts.

25 Similar reference-letters indicate corresponding parts throughout.

The runner A and sole-plate B are preferably connected by machine-screws C, which make a neat, firm, and economical means of 30 attaching the two parts. Said screws pass loosely through openings in said plate B and are threaded to openings in said runner A, and by reason of their heads the two parts are strongly clamped together. The rear end 35 of this sole-plate is provided with the usual upward projections b, which are formed with serrations on their inner side for engaging the heel of a boot.

The most essential feature of my invention 40 is a threaded lever by which the sole and heel clamps of a skate may be set to various sizes of boots and after such adjustment be attached to or detached from said boot by a single movement.

45 I do not confine my invention to a threaded lever in connection with a particular mechanism for adjusting the clamps. In the drawings I show one mechanism, however, to which my improvements readily apply. This comprises a plate D, which is placed upon the sole-plate B, covering the sole-clamps E and rendered longitudinally movable thereon by

means of a slot d, through which is passed a screw C', threaded to an opening in the plate B and runner A, the clamps E having at their 55 inner ends upward projections e, entering inclined slots d' d', formed in said plate D, by which their required movement is obtained. The rear part of said plate D may be held steady by means of a screw passing downward through said rear end and through a slot b', formed in the sole-plate B, and then threaded to a collar or swiveled bearing F, which carries one end of my improved actuating-lever G; or the said collar or bearing 60 F may be provided with an integral stud f, extending upward through the slot b' of the plate B, and an opening formed for the purpose in the rear part of said plate D, in which the said stud f is swiveled.

70 The actuating-lever G may comprise a threaded portion g, a smooth cylindrical portion g', and (preferably) a milled portion g'' at or near its free end; but said free end may be flattened in order to be grasped and turned 75 easily by the fingers; or a short pin may be put through it and answer a good purpose. Upon said threaded portion g is fitted a suitable nut H, which is swiveled, by means of a projecting stud h, to one end of an arm I, 80 which may be secured underneath the sole-plate, and pivoted to an adjustable heel-clamp J by a screw or suitable rivet j, said rivet having free movement forward or back within the slot b'', formed for this purpose in the 85 sole-plate B.

In Figs. 1 and 3 the free end of the actuating-lever G is flattened out somewhat and provided with an ear at each side for setting over the runner when the skate is locked 90 upon a boot; but when said lever is made as shown in Fig. 4 it is slipped into a hook i, formed at the rear end of the arm I, and thus held parallel with the runner A.

An ear j may be formed upon the heel-clamp J, fitting the slot b'' in the sole-plate, for preventing any lateral movement of same, as seen in Fig. 2.

To set this improved skate to a boot, the wearer has only to pull the lever G out one side, as in Fig. 3. Then place the skate on the boot and revolve said lever G until the clamps E and J are brought in contact with the boot. Then, by shutting the free end of

said lever either over the runner, as in Fig. 1, or the hook *i*, as in Fig. 4, the skate is firmly fastened to the foot.

Having described my improvements, what I claim as new, and desire to secure by Letters Patent, is—

1. The combination of an adjustable plate having at one end an upward projection for engaging the heel of a boot and at the other end a block or nut swiveled to the under side and containing a horizontally-threaded opening, and an actuating-lever having its forward end swiveled to a plate for adjusting the sole-clamps and provided with a central threaded portion confined within said nut or threaded block, all substantially for the purpose set forth.

2. The combination, with a plate for actuating the sole-clamps and an adjustable heel-clamp, of a threaded actuating-lever, and a swiveled arm provided at one end with a swiveled nut connecting the threaded portion of said lever with said adjustable heel-

clamps, substantially for the purpose set forth.

3. In clamping mechanism for skates, an arm or link for connecting the actuating-lever with the adjustable heel-clamp, having at one end a suitable hook for the reception of the free end of said lever, substantially for the purpose set forth.

4. In clamping mechanism for skates, the combination, with an actuating-lever having a threaded portion, of an arm or link having at one end a swiveled nut fitting the thread on said lever, its opposite end being attached to an adjustable heel-clamp, and provided with a suitable hook for the reception of the free end of said lever, all for the purpose described.

In testimony whereof I affix my signature in presence of two witnesses.

JOHN H. YOUNG.
